CLAIM

The ornamental design for an elephant-shaped sound machine, as shown and described.

DESCRIPTION

FIG. 1 is a perspective view taken from the top, front, and left side of an elephant-shaped sound machine of the present design.

FIG. 2 is a front elevation view of the elephant-shaped sound machine of FIG. 1.

FIG. 3 is a rear elevation view of the elephant-shaped sound machine of FIG. 1.

FIG. 4 is a left side elevation view of the elephant-shaped sound machine of FIG. 1.

FIG. 5 is a right side elevation view of the elephant-shaped sound machine of FIG. 1.

FIG. 6 is a top plan view of the elephant-shaped sound machine of FIG. 1; and,

FIG. 7 is a bottom plan view of the elephant-shaped sound machine of FIG. 1.

The broken lines illustrate unclaimed portions and form no part of the claimed design.
